PARTITION POST

Filed June 13, 1927

BY

INVENTOR
JACOB H. SIMON.
Richard J. Dwoske
ATTORNEY

UNITED STATES PATENT OFFICE.

JACOB H. SIMON, OF BROOKLYN, NEW YORK.

PARTITION POST.

Application filed June 13, 1927. Serial No. 198,563.

This invention relates to partitions and in particular to partition brace members of an extendable nature.

A particular object of the invention is to provide a partition brace or post which may be used between partition pieces to effectively hold the same together and to reduce the length of time necessary in the erection of partitions in rooms having ceilings of various heights.

A further object of the invention is to provide a partition post which is extendable and which when in any of its extended positions is arranged to accommodate, in the grooves formed in the sides thereof, the edges of the partition to be held.

A still further object of the invention is to provide a particular kind of partition post, the two pieces of which are made in identically the same manner and which are reversed and held together in sliding arrangement due to their peculiar construction.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

Figure 1 is a view in perspective of a portion of a partition showing the use in connection therewith of my improved partition post.

Figure 2 is an enlarged section on the line 2-2 of Figure 1 showing the construction of the partition post and also of the wall engaging member.

Figure 3 is a view in end elevation of one of the members which go to make up the partition post.

Figure 4 is a view similar to Figure 3 showing the other member that goes to make up the partition post.

Figure 5 is a view in end elevation of the wall member which is arranged to hold the partition supporting element.

Figure 6 is a view in end elevation of the partition supporting element adapted to be used in connection with the wall member shown in Figure 5, and

Figure 7 is a sectional view showing how wooden partitions or hollow steel partitions may be joined by a channel member which

is a unit in the construction of my improved partition.

Figure 8 is a view in end elevation of a further modified form of construction.

Referring to the drawings in detail, 5 indicates generally a panel which may be made of wood, steel or other metal construction and which is arranged to be put up in sections to divide off a large area into rooms, for office use, for instance.

It has been found in the erection of partitions of this kind that a great number of parts are necessary in the erection of wooden partitions and doors and openings in the partitions have to be planned for in advance to be properly positioned and with a view to overcoming this objection, I have provided an extendable partition post which allows partitions to be built up to any height in order to reach the ceiling, it of course being understood that the partitions will be cut to suit the height of the ceiling and will be joined by my improved partition post.

The partitions 5 are cut to any width and height and, in erecting a partition, as shown in Figure 1, the wall strip 6 is placed in position and suitably nailed, screwed or otherwise secured to the wall 7, after which the partition is placed therein. This wall strip is made up of the flat piece 8 having over-turned edge portions 9 which are adapted to receive the edge flanges 10 of the partition holding member 11, this piece being pressed out of a single piece of material to provide guide ribs 12 between which the end of the partition is positioned.

The fastening element indicated by the numeral 13 may pass through the bottom of the partition holding member 11 and through the wall member 6 to securely retain the two in connection with the wall and in position to receive the partition indicated by the numeral 14. This partition is made up in any shape or style, may be made of metal or wood and may come in lengths so that it may be cut to suitable heights to fit in depending upon the height of the ceiling from the floor.

The opposite end of the partition 14 is arranged to receive the partition post, the object of the partition post being to join two sections of partitions so that they are held securely in place and make a solid wall without the necessity of cutting or making up suitable parts to fit a given distance.

In order to provide these telescopic posts,

I make up a member 15 which is provided with an overturned flange 16 and a bent-over flange or end 17, the body portion 15 of the member being bent upon itself as at 18 to 5 form a receiving slot for the flange 17 of a companion member, which is made in identically the same manner and is telescoped as shown in Figure 2 into its companion member. The turned over portion 16 of each being adapted to receive the flange 17 of each 10 while the turned over portions 18 are arranged to give a resiliency when the partitions are placed in the partition post. It will be evident that the combination of these members 15 will give a telescopic partition post which is adapted to fit over one side of a partition 5 and to receive the partition 19 in the opposite side thereof, the flanges 16 or turned over portions extending outward so as to provide a resilient lip whereby when the partition is placed in position, it is releasably held 20 due to the friction of the bent over portion 16.

It is quite evident, of course, that the partition post may be extended to accommodate 25 any height of partition and the partitions themselves may be given a finished appearance through the use of suitable moulding 20. In order to provide a joint for the partitions, I may also make use of a channel member 30 21 which, in its side portions 22, is adapted to be secured to the ends of the partitions 23 and 24 through the medium of suitable rivets or pins 25.

It is evident that this connection joins the 35 partitions together very securely and gives them the necessary rigidity.

It is also evident that I have provided a new and improved telescopic partition post which may be extendable any distance to accommodate different sizes or lengths of par-

titioning and one which may be not only used vertically but may be adapted for use longitudinally of the partitions, if the conditions require it.

It is evident, of course, that the partition 45 post may be produced in quantity due to the fact that they are identical in construction, one fitting within the other in sliding relation as shown in Figure 2 and the construction being such that they are adapted to be 50 readily assembled and cut into any length required.

It is evident, also, that I have provided a wall partition holding member which may be made up in any length and which may be extended to suit the conditions.

It is evident also, that a four piece member may be used consisting of the inner members 26 which are held together by the outer or edge channels 27 as illustrated in Figure 8. 60

While I have illustrated and described my invention with some degree of particularity, I realize that in practice various alterations therein may be made. I therefore reserve the right and privilege of changing the form of 65 the details of construction or otherwise altering the arrangement of the correlated parts without departing from the spirit of the invention or the scope of the appended claim.

Having thus described my invention, what 70 I claim as new and desire to secure by United States Letters Patent is:—

A partition joining member comprising a body portion, inwardly bent flanges at the side edges of said body portion and the 75 flanges being arranged to resiliently engage and hold together the ends of the partition.

In testimony whereof I affix my signature.

JACOB H. SIMON. [L. S.]
